OUTER JACKET OF CRYOGENIC STORAGE VESSELS

John Terlesky, New Brighton, Pa., assignor to Pittsburgh-
Des Moines Steel Company, Pittsburgh, Pa.

Filed Sept. 16, 1971, Ser. No. 181,282

Term of patent 14 years

Int. Cl. D23—01

U.S. Cl. D23—2

FIG. 1.

FIG. 2.

FIG. 3.

FIG. 1 is a front elevational view of the outer jacket of cryogenic storage vessels, showing my new design;

FIG. 2 is a cross sectional view taken on line 2—2 of FIG. 1 looking in the direction of the arrows; and

FIG. 3 is a cross sectional view taken on line 3—3 of FIG. 1 looking in the direction of the arrows.

I claim:

The ornamental design for an outer jacket of cryogenic storage vessels, as shown.
